(57) **CLAIM**

The ornamental design for a drill template, as shown and described.

DESCRIPTION

FIG. 1 is a top, front, right perspective view of a drill template showing my new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken lines immediately adjacent to the shaded area represent unclaimed boundaries of the design.

1 Claim, 3 Drawing Sheets

FIG. 1

FIG. 2**FIG. 3****FIG. 4****FIG. 5**

FIG. 6**FIG. 7**
